(57) **CLAIM**

I claim the ornamental design for a hand-held wiper device for solid and liquid waste, as shown and described.

DESCRIPTION

FIG. 1 is a front perspective view of the hand-held wiper device for solid and liquid waste.

FIG. 2 is a rear perspective view thereof.

FIG. 3 is front view thereof.

FIG. 4 is a back view thereof.

FIG. 5 is a top view thereof.

FIG. 6 is a bottom view thereof.

FIG. 7 is a right side view thereof; and,

FIG. 8 is a left side view thereof.

The dotted lines represent portions of the hand-held wiper device for solid and liquid waste that form no part of the claimed design.

1 Claim, 5 Drawing Sheets
